HEATING OF FLUIDS

Walter C. Hensel, Chicago, Ill., assignor to Universal Oil Products Company, Chicago, Ill., a corporation of Delaware

Application April 20, 1942, Serial No. 439,737

5 Claims. (Cl. 122—510)

This invention relates to improved supporting means for tubular heating elements and more particularly to a supporting means for tubular elements which are subjected to high rates of heating.

More specifically, this invention relates to tubular heating element supporting means having passageways therethrough which are open at opposite ends to the atmosphere and the combustion and heating zones of the heater. The pressure differential between the exterior and interior ends of said passageways will induce therethrough a flow of air which will cool the supports and prevent their failure due to overheating. The present invention is also applicable to heaters employing forced or induced draft, as well as those utilizing natural stack draft.

It has heretofore been the general practice in designing heaters for high temperature service to employ tube supports comprising various alloy steels, such as those containing chromium and nickel or high temperature cast irons, such as Meehanite. There are, however, maximum allowable temperatures to which these materials may be subjected and still retain the physical characteristics necessary to prevent their failure or distortion. The trend in modern heater designs, especially in the oil refining industry, has been toward steadily increasing rates of heat input to the fluid conduit. This is accomplished by locating the fluid conduit within the combustion zone of the furnace wherein it is exposed to high rates of direct radiant heat. The design of suitable supporting means for such fluid conduits has become an ever increasing difficulty but may be overcome by employing the present invention.

Heretofore a satisfactory answer to the problem of supporting fluid conduits located in such extremely high temperature zones has not been disclosed. There are various known means for cooling the main structural members of the support, but no means have been provided for cooling those portions of the support which are located in the hottest part of the heating zone and whose function is important in supporting and retaining the individual tubular elements of the fluid conduit in their desired locations. The present invention provides means for cooling substantially the entire fluid supporting member and especially those portions of said member which are subjected to the highest temperatures and which would normally be the first to fail due to overheating.

The accompanying diagrammatic drawings il-

lustrate one of the many forms of apparatus embodying the features of the invention and it and a subsequent description thereof are included in this specification in order that the features and advantages of the invention may be more clearly understood.

Fig. 1 of the drawings illustrates, principally in section, a cross-sectional elevational view of one form of heater embodying the features of the invention.

Fig. 2 illustrates an enlarged elevational view of one of the supporting members with a portion cut away to show the interior construction.

Fig. 3 is a view of the member shown in Fig. 2 taken from a plane indicated by line 3—3.

Fig. 4 illustrates a sectional plan view of a modified arrangement of the tube support shown in Figs. 2 and 3 with insulation added to its exterior surface.

Referring now to Figs. 1, 2 and 3, the heater herein illustrated and generally referred to as a center wall updraft heater is comprised of combustion and heating zones 1 and 1' which are located on opposite sides of vertical center wall 2. Combustion and heating zones 1 and 1' are defined by the side walls 3 and 3', end wall 4 and its opposing end wall not shown, and the floor 5, all of which may be made up of satisfactory refractory materials of monolithic or built-up construction. The upper portions of walls 3 and 3' converge toward the center to form a zone of restricted cross-sectional area 6 directly above the center wall 2. Buck stays 7 are provided adjacent the outer walls of the heater to act as supporting means therefor and the entire heater may be supported on the foundation 8. The entire heater may be enclosed by a sheet metal shell 13 secured to the outer flanges of buck stays 7 thus providing air spaces 22 between said shell and the walls 3 and 3'. Suitable burners 9 supplied through conduit 10 with, in this case, gaseous fuel regulated by valve 11 are disposed below the floor 5. Air for combustion will be drawn through louvres 14 and be directed in a downward direction paralleling the buck stays 7 by the draft action of the stack. The desired combustible mixture of fuel gas and air will be accomplished in mixer 15, and said mixture will be introduced through ports 12 in floor 5 to the combustion zones of the heater. Any desired excess air may be regulated by adjusting the relationship between burner nozzles 16 and ports 12.

Adjacent the vertical walls 3 and 3' and the sloping portions thereof in the heater here illustrated are disposed a row of parallel tubular

heating elements 17. It is, of course, entirely within the scope of the invention to employ more than a single row of heating tubes adjacent the walls. In the restricted section of the heater there is a double row of tubes 18 which are disposed in staggered arrangement. Tubes 17 and 18 are located substantially within the combustion zone of the heater and are subjected to high rates of heating and it is the purpose of the invention to provide supporting means therefor. It is the general practice in heaters of this type to provide a plurality of tubular elements in the space located directly above the tubes 18 but as this is a relatively cooler zone, tube supporting means for these elements have not been a great problem and, therefore, to simplify the drawings these tubes are not shown. Tubes 17 are supported by means of a plurality of members 19 which are secured to buck stays 7 by suitable bolts 20. These members are substantially hollow castings provided with openings 21 which provide means of communication between the air space 22 and the interior of said members. Small ports or weep holes 23 are provided in the projecting portions 24 of the member 19 and furnish means of communication between the interior of said members and the combustion zone of the heater. Tubes 18 are supported from the buck stays by means of a substantially hollow member 25. Member 25 is provided with ports 26 and small ports 27 in communication with the air space 22 and interior of the heater, respectively, and is secured to the buck stays by suitable bolts 20.

In cases where extremely high temperatures are generated within the heater, suitable insulation may be applied to the exterior surface of the members, as shown in Fig. 4. This insulation 28 may be retained in place by the lugs 29 attached to the supporting member, for example, as illustrated in my recently issued Patent No. 2,270,297.

When the heater is in operation, the pressure differential between the atmosphere and the interior of the heater will induce a flow of air through the several supporting members thereby causing the cooling thereof and preventing their failure due to overheating.

I claim as my invention:

1. In combination with a furnace, walls forming a combustion and heating zone, heating tubes within said zone adjacent one of the fur-

nace walls, a hollow supporting member projecting through the last-named wall and communicating with the atmosphere outside the furnace, recesses in said member for receiving said tubes, a port in said member opening into the interior of said combustion and heating zone, and means for inducing the flow of air through said member into said zone.

2. In combination with a furnace having a vertical wall and a horizontal heating tube within the furnace adjacent said wall, a hollow supporting member projecting through said wall and communicating with the atmosphere outside the furnace, said member being recessed to receive said tube, a port in said member opening into the interior of the furnace, and means for inducing the flow of air through said member into the furnace.

3. In combination with a furnace having a vertical wall and a plurality of vertically spaced horizontal heating tubes within the furnace adjacent said wall, a hollow supporting member projecting through said wall and having an opening outside the furnace, additional openings in said member in the portion thereof disposed within the furnace, said member being provided with vertically spaced recesses to receive said tubes, and means for inducing the flow of air through said member from the first-mentioned opening to said additional openings.

4. In combination with a furnace having horizontal heating tubes therein, a hollow member projecting through a wall of the furnace and having a recessed portion adapted to engage and support at least one of said tubes, said member being provided with an opening outside the furnace and an opening within the furnace, and means for inducing the flow of air through said member from the first-mentioned opening to the second-mentioned opening.

5. In combination with a furnace having horizontal heating tubes therein, a hollow member projecting through a wall of the furnace and having recesses for supporting a plurality of said tubes, said member being provided with an opening outside the furnace and additional openings within the furnace adjacent the tube supporting recesses, and means for inducing the flow of air through said member from the first-named opening to said additional openings.

WALTER C. HENSEL.
